Continuation of application Serial No. 675,242,
June 7, 1946. This application November 18,
1950, Serial No. 196,372

17 Claims. (Cl. 261—41)

1

This invention relates to carburetors for internal combustion engines, and particularly to carburetors of a type now used extensively on aircraft, such as disclosed in U. S. Patents to Twyman, 2,391,755, December 25, 1945, and Chandler, 2,394,664, February 12, 1946.

This application is a continuation of my application, Serial No. 675,242, filed June 7, 1946, and later abandoned.

In such carburetors, it is customary to provide means whereby the pilot, or other person in charge of the engine, can manually select either a rich fuel-air mixture or a lean fuel-air mixture. The rich mixture is generally used under high power output conditions, such as takeoff, climbing and high speed. The lean mixture is used under cruising conditions for purposes of economy. Engines tend to run hotter with lean mixtures than with rich mixtures. The carburetor is usually so designed that the lean mixture obtained by manual selection is about as lean as can be used under cruising conditions without overheating. The mixture so supplied is too lean for safe use under high power output conditions. It sometimes happens that the pilot forgets that he has set his mixture control in the lean position and attempts to operate the engine at high power output. This may result in overheating of the engine. Enrichment valves are therefore customarily provided to increase the fuel-air ratio at the higher power outputs.

In carburetors of the type described herein, the mixture control takes the form of a pair of parallel passages, each having a metering restriction in it, and a selector valve movable between a lean position wherein only one passage is open to the flow of fuel and a rich position wherein both passages are open. The enrichment valve takes the form of a valve connected in parallel with the restriction in the one "lean" passage and movable in an opening direction by the fuel pressure differential across the restriction. The fuel pressure differential is varied by suitable mechanism as a function of the engine power output. The enrichment valve is spring biased to closed position. The strength of the biasing spring determines the value of fuel pressure differential, and hence of power output, at which the enrichment valve starts to open, and the rate at which its opening increases with increasing power output.

Since the range of useful fuel-air ratios has a definite upper or rich limit as well as a lean limit, some means must be provided for limiting the flow thru the enrichment valve. Since this

upper limit of useful fuel-air ratios is not affected by the position of the manual mixture control, it is usually desired to have the same upper limit of fuel-air ratio regardless of the mixture control position. It has been the practice in the past to achieve this limiting effect by providing an additional metering restriction to receive both the discharge from the enrichment valve and the discharge from the "rich" metering restriction. Such a limiting restriction effectively established an upper limit to the fuel-air ratio and the upper limit was the same at both positions of the mixture control valve. See patents to Twyman and Chandler, cited.

10 The series limiting restriction had one undesirable feature. When the mixture control was in its lean position, there was no flow thru the limiting restriction until the enrichment valve opened. Hence there was no pressure drop thru the limiting restriction and the total fuel pressure differential across the fuel metering system was available to open the enrichment valve against the biasing action of its spring. However, when the mixture control was in its rich position, there was a flow thru the limiting restriction at all times. The resulting pressure drop thru the limiting restriction reduced the fuel pressure differential available to open the enrichment valve. Hence the enrichment valve did not open until the total fuel pressure differential across the fuel metering system was somewhat higher than the fuel pressure differential required to open the enrichment valve when the mixture control was in its lean position. In other words, when the mixture control was in its rich position, a higher power output was required to begin opening of the enrichment valve than when the mixture control was in the lean position. Since it is necessary that the enrichment valve open after a certain power output is exceeded,

15 20 25 30 35 40 45 50

regardless of the position of the manual mixture control, it was customary to design the enrichment valve spring so that the enrichment valve opened at the required value of power output with the mixture control in its rich position. The result was that when the mixture control was in its lean position, the enrichment valve opened at a lower value of power output, where it was actually not needed. This resulted in a waste of fuel. It was especially undesirable because the high fuel consumption occurred under conditions (mixture control set lean and engine running at highest "cruising" power output) where the best efficiency should be expected.

It is, therefore, an object of this invention to

provide an improved carburetor for an internal combustion engine.

Another object is to provide, in a carburetor having a manual mixture control movable between lean and rich positions, improved enrichment valve mechanism responsive to fuel pressure differential and opening at the same value of fuel pressure differential regardless of the mixture control position.

Another object is to provide, in a carburetor of the type described, improved enrichment valve mechanism, whereby the same rich mixture is obtained at high power outputs, regardless of the position of the manual mixture control.

Other objects and advantages of the present invention will become apparent from the consideration of the appended specification, claims and drawing, in which:

Figure 1 represents, somewhat diagrammatically, a carburetor for an internal combustion engine embodying the principles of my invention; and Figure 2 shows the various fuel/air ratios at various air flows to the engine, and the effect of the enriching fuel flows on said ratios.

In the drawing, air flows thru a carburetor body 10 from an entrance 12, past a venturi 14, a throttle 16 and a fuel discharge nozzle 18 to a mixture outlet 20. The mixture passes from the outlet 20 to the engine. In most cases, a supercharger is used between the outlet 20 and the engine. In some cases a second supercharger is used upstream from the entrance 12.

Air flowing thru the venturi 14 creates an air pressure differential between the entrance and throat of the venturi, which differential varies with the velocity of the air flowing. This air pressure differential is utilized to create a flow of air thru a secondary air conduit connecting the entrance and throat of the venturi. A plurality of impact tubes 22 are provided in the entrance 12, with their ends open to receive the impact of the entering air. Air flowing thru the secondary conduit just mentioned enters these impact tubes 22 and passes to a common passage 24, usually termed a vent ring. From the vent ring 24, the air flows thru a conduit 26, a chamber 28 in a fuel meter generally indicated at 30, a fixed restriction 32, an expandable chamber 34 in the fuel meter 30, a conduit 36, past a valve 38 into a chamber 40, and thence thru a conduit 42 to the throat of venturi 14.

Valve 38 is positioned by a bellows 44 located in the chamber 40. The bellows 44 is sealed so as to expand and contract with variations in pressure in chamber 40. The bellows 44 is preferably partially filled with nitrogen or other suitable fluid having an appreciable coefficient of thermal expansion, so that it also expands and contracts with variations in the air temperature. Since the bellows 44 responds to both temperature and pressure, it may be said to respond to air density. The valve 38 is contoured with relation to the response characteristics of the bellows 44 so that the pressure differential appearing across the fixed restriction 32 in the fuel meter 30 is an accurate measure of the mass rate of air flow passing thru the venturi. In other words, the bellows operated valve 38 compensates for changes in density of the air passing thru the venturi.

Fuel enters the carburetor from a pump (not shown) and flows thru a conduit 50, past a valve 52 in the fuel meter 30, thru a conduit 54, to a mixture control 56 including a disc valve 58.

fixed on a shaft 60. From the mixture control 56, the fuel flows thru one or both of a pair of parallel conduits 62 and 64 into a jet system 66. From the jet system 66, the fuel flows thru an idle valve 68, a conduit 70, a pressure regulator 72 and a conduit 74 to the fuel discharge nozzle 18.

The fuel meter 30 includes a chamber 76 in addition to the expandable chambers 28, 34 and 53 previously described. Chambers 76 and 28 are separated by a flexible diaphragm 78. Chambers 28 and 34 are separated by a flexible diaphragm 80, and chambers 34 and 53 are separated by a flexible diaphragm 82. The three diaphragms 78, 80 and 82 are attached at their centers to the stem of the valve 52, which is balanced against inlet pressure. Chamber 76 is connected thru a conduit 84 to the conduit 70 in the fuel line on the downstream side of the jet system 66. Chamber 53 is, of course, supplied with fuel at the pressure existing on the upstream side of the jet system. It may, therefore, be seen that the valve 52 is positioned in accordance with the balance between a downwardly acting force which is a measure of the rate of flow of air to the engine, and an upwardly acting force which is a measure of the rate of flow of fuel to the engine. The downwardly acting force is the difference between the pressures in chambers 28 and 34, which difference is applied to the diaphragm 80. The upwardly acting force is the difference between the pressures in chambers 53 and 76, which is the fuel pressure differential across the jet system. Whenever the fuel flow is disproportionate with respect to the air flow, the valve 52 is moved to correct the fuel flow and maintain the same fuel-to-air ratio as before. The foregoing statement, with respect to the constant fuel-air ratio, assumes that the cross-sectional area in the jet system open to the flow of fuel therethru is a constant. This, however, is not strictly constant, but is varied manually and automatically under certain conditions.

Fuel entering the jet system 66 thru conduit 62 may pass thru a restriction 86 directly to the outlet of the jet system. It may also pass thru a passage 88 controlled by an enrichment valve 90 biased to closed position by a spring 92. Fuel passing thru the conduit 64 flows thru a fixed restriction 93. The opening movement of valve 90 is limited by a stop 94. A branch conduit 96 is provided, which connects the conduits 62 and 64 at points upstream from the restrictions therein. Flow thru the conduit 96 is controlled by a check valve 98, biased to closed position by a spring 100.

When the disc valve 58 of the mixture control 56 is in the position shown in full lines in the drawing, which is termed the "lean" position, fuel may enter the jet system only thru the conduit 62. With the valve 58 in its "rich" position, as shown in dotted lines on the drawing, fuel may enter the jet system thru both conduits 62 and 64.

When the valve 58 is in its lean position, a first predetermined relationship is established between the fuel pressure differential across the jet system and the rate of flow of fuel. When the valve 58 is in its rich position, a second such relationship is established, such that a greater fuel flow is obtained for each value of fuel pressure differential. Since the fuel meter 30 establishes a fixed relationship between the mass air flow and the fuel pressure differential, it may be seen that movement of valve 58 be-

tween its "lean" and "rich" positions selects respectively smaller and greater fuel-air ratios.

The enrichment valve 90 opens under high fuel pressure differential conditions, which correspond generally to conditions of high power output, to increase the fuel-air ratio. It should be noted that the operation of valve 90 is the same whether the mixture control is in its lean or rich position. The stop 94 limits the enrichment effect which is produced by valve 90.

When the mixture control is in its lean position, the fuel pressure above the check valve 98 is the fuel pressure on the upstream side of the jet system, while the fuel pressure under the valve 98 is substantially the fuel pressure on the downstream side of the jet system. Therefore the full fuel pressure differential across the jet system acts on the valve 98, tending to open it. When this fuel pressure differential exceeds a value determined by the strength of spring 100, the valve 98 opens. If the fuel pressure differential continues to increase, the valve 98 opens wider. After it reaches its wide open position, the relationships between the fuel pressure differential across the jet system and the total fuel flow thru the jet system are substantially the same as when the mixture control is in its rich position, even though the manual mixture control may actually be in its lean position. It is usually desirable to establish the rates of springs 92 and 100 so that valve 98 opens at a somewhat higher fuel pressure differential than valve 90.

When the mixture control is in its rich position, the fuel pressures on the opposite sides of valve 98 are the same, and the valve therefore remains closed under the influence of its biasing spring 100.

In the chart of Figure 2, the ordinates denote fuel/air ratios of the fuel/air mixture delivered to the engine, and the abscissas denote percentages of maximum air flow to the engine throughout its range of operation from minimum to maximum speed and power output. The curve ABCDEF represents the fuel/air ratios that obtain at various rates of air flow from minimum to maximum speed and power output, when the manual mixture control 58 is in its rich position, while curve AGHIEF denotes the corresponding fuel/air ratios that obtain when the manual mixture control is in its lean position.

From these curves, it will be noted that the horizontal portion BC of the rich curve, and GH of the lean curve, show the respective constant mixture ratios that are obtained when the manual mixture control is in its rich and lean positions, before the enrichment valve 90 commences to open (i. e., between approximately 30 and 60 per cent of maximum air flow). At point C on the rich curve and point H on the lean curve, the fuel pressure differential reaches a value sufficient to commence the opening of enrichment valve 90. As valve 90 continues to open wider with increasing air flow (and corresponding fuel pressure differential), and the manual mixture control is in its rich position, the fuel/air ratio is progressively increased, as shown by the portion CDE of the rich curve. At point E (at approximately 90 per cent of maximum air flow), the stop 94 limits the further opening of valve 90, whereupon the fuel/air ratio reaches its maximum value and remains constant at that value when the air flow further increases from 90 to 100 per cent.

of maximum air flow, as shown by the horizontal portion EF of the rich curve.

Similarly, when the manual mixture control is in its lean position, the opening of valve 90 with increasing air flow progressively increases the fuel/air ratio, as shown by the portion HI of the lean curve. When the manual mixture control 58 remains in its lean position and the air flow increases beyond point I (at about 80 per cent of maximum air flow), valve 98 commences to open, and the fuel/air ratio is progressively increased by the further opening of both 90 and 98, as shown by the portion IE of the lean curve. At point E, both valves 90 and 98 are at their maximum opening and the fuel/air ratio is at its maximum value, and remains constant at such value when the air flow further increases from 90 to 100 per cent of maximum air flow, as shown by the horizontal portion EF of the lean curve.

It will further be noted, from Fig. 2, that the curved portions CD and HI of the rich and lean curves are parallel which indicates that the rate of enrichment from 60 to 80 per cent of maximum air flow is the same, regardless of whether the manual mixture control 58 is in its rich or lean position. When the air flow increases from 80 to 90 per cent of maximum air flow, and mixture control 58 is in its rich position, valve 98 does not open, hence the fuel air ratio is increased only by the further opening of valve 90. However, if mixture control 58 is in its lean position, the increase of air flow from 80 to 90 per cent causes valve 98 to open, and the fuel/air ratio increases from point I to point E at a greater rate than between points D and E on the rich curve (when 98 is closed). Since the lean curve coincides with the rich curve from points D to E, it will be seen that the maximum fuel/air ratio is the same, regardless of whether the mixture control 58 is in its lean or rich position. It is also to be noted that the portion EF of both rich and lean curves is horizontal, denoting a constant fuel/air ratio, during a substantial portion (e. g., 10 per cent) of the operating range of the engine.

From the foregoing, it may be seen that the valve 98 insures that if the engine is operated at high power output with the manual mixture control in the lean position, then the actual mixture delivered to the engine will be just as rich as if the manual control had been moved to its rich position. It may also be seen that the enrichment flow thru valve 90 is limited by stop 94, and that the flow thru valve 98 is limited by restriction 93.

The idle valve mechanism 68 includes a valve member 102 movable by means of an arm 104 connected thru a link 106 to an arm 108 on the shaft 110 of the throttle 16. It will be noted that a spring 112 is provided, biasing the valve 52 toward open position. The spring 112 and the valve 102 cooperate to control the fuel flow to the engine under conditions of light load. When the engine is producing substantial power, the throttle 16 is fairly wide open, and the valve 102 is retracted to a position where it does not appreciably restrict the fuel flow. As throttle 16 approaches its closed position, the valve 102 is moved concurrently with the throttle to increasingly restrict the fuel flow. At the same time, the air flow thru the venturi 14 is becoming less due to the restricted position of the throttle, so that the air pressure differential

acting on diaphragm 80 is becoming very small. Under such conditions, the spring 112 becomes the predominating downward force acting on valve 52. The action of spring 112 may be described by saying that it sets a minimum fuel pressure differential across the jet system. If the downward force due to the air pressure differential on diaphragm 80 be neglected, which is permissible under engine idling conditions, then it may be said that the spring 112 establishes a constant fuel pressure differential across the jet system, and that the valve 102 controls the fuel flow obtained with that constant fuel pressure differential in accordance with the contour of valve 102 and the throttle position. Such an arrangement is necessary because of the inaccuracy of the air flow measuring system at very low flows.

The pressure regulator 72 is provided to prevent variations in pressure at the fuel nozzle 18 from affecting the flow thru the jet system. The regulator 72 includes a valve 114 biased to closed position by a spring 116. A diaphragm 118 separates a pair of expansible chambers 120 and 122. The chamber 120 receives fuel at the pressure on the downstream side of the jet system, while chamber 122 is vented to vent ring 24 thru conduit 124 and conduit 26. The effect of this arrangement is to maintain a substantially constant pressure on the downstream side of the jet system.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim as my invention:

1. A fuel supply system for an internal combustion engine, comprising a main conduit for fuel flowing to said engine, a pair of parallel branch conduits connecting two spaced portions of said main conduit, a selector valve at one of the junctions of said branch conduits with said main conduit, said selector valve being movable between a first position wherein only one of said branch conduits is open and a second position wherein both said branch conduits are open, metering restrictions in each of said branch conduits for determining the rate of fuel flow to the engine throughout its operating range, means for controlling the fuel pressure differential between said portions of said main conduit, said selector valve being effective upon movement to said first and second positions to establish respectively first and second relationships between said fuel pressure differential and the rate of flow of fuel to said engine, a third branch conduit connecting said pair of branch conduits at points between said selector valve and said restrictions, a check valve in said third branch conduit, spring means biasing said check valve closed, said check valve being inoperable when said selector valve is in said second position and being operable to open position by the fuel pressure differential when said selector valve is in said first position and said pressure differential exceeds a value determined by the characteristics of said spring means, whereby, when said pressure differential exceeds said value, the rate of flow of fuel to the engine is gradually increased to the same constant maxi-

mum value whether the selector valve is in its first or second position.

2. Fluid flow control apparatus, comprising a main conduit, a pair of parallel branch conduits connecting two spaced portions of said main conduit, a selector valve at one of the junctions of said branch conduits with said main conduit, said selector valve being movable between a first position wherein only one of said branch conduits is open and a second position wherein both of said branch conduits are open, metering restrictions in each of said branch conduits for determining the rate of fuel flow to the engine throughout its operating range, said selector valve being effective upon movement to said first and second positions to establish respectively first and second relationships between the fluid pressure differential between said portions of said main conduit and the rate of flow of fluid therethru, a third branch conduit connecting said pair of branch conduits at points between said selector valve and said restrictions, a check valve in said third branch conduit, and spring means biasing said check valve closed, said check valve being inoperable when said selector valve is in said second position and being operable to open position by said fluid pressure differential when said selector valve is in said first position and said pressure differential exceeds a value determined by the characteristics of said spring means, whereby, when said pressure differential exceeds said value, the rate of flow of fluid thru said main conduit is gradually increased to the same constant maximum value whether the selector valve is in its first or second position.

3. A fuel supply system for an internal combustion engine, comprising a main conduit for fuel flowing to said engine, a pair of parallel branch conduits connecting two spaced portions of said main conduit, a selector valve at one of the junctions of said branch conduits with said main conduit, said selector valve being movable between a first position wherein only one of said branch conduits is open and a second position wherein both said branch conduits are open, metering restrictions in each of said branch conduits for determining the rate of fuel flow to the engine throughout its operating range, means for controlling the fuel pressure differential between said portions of said main conduit, said selector valve being effective upon movement to said first and second positions to establish respectively first and second relationships between said fuel pressure differential and the rate of flow of fuel to said engine, a third branch conduit connecting said pair of branch conduits at points between said selector valve and said restrictions, a check valve in said third branch conduit opening in the direction of flow from said one branch conduit to the other, spring means biasing said check valve closed in opposition to the difference between the fuel pressures acting on opposite sides thereof, said check valve being inoperable when said selector valve is in said second position and being operable to open position by said difference of fuel pressures when said selector valve is in said first position and said pressure differential exceeds a value determined by the characteristics of said spring means, whereby, when said pressure differential exceeds said value, the rate of flow of fuel to the engine is gradually increased to the same constant maximum value whether the selector valve is in its first or second position.

4. A fuel supply system for an internal combustion engine, comprising a conduit for com-

bustion air flowing to said engine, means associated with said conduit for producing two unequal air pressures whose difference is a measure of the rate of flow of air thru said conduit, a main conduit for fuel flowing to said engine, a pair of parallel branch conduits connecting two spaced portions of said main conduit, a selector valve at the upstream junction of said branch conduits with said main conduit, said selector valve being movable between a first position wherein only one of said branch conduits is open and a second position wherein both said branch conduits are open, metering restrictions in each of said branch conduits for determining the rate of fuel flow to the engine throughout its operating range, means responsive to the difference between said two unequal air pressures for controlling the fuel pressure differential between said portions of said main conduit, said selector valve being effective upon movement to said first and second positions to establish respectively first and second relationships between said fuel pressure differential and the rate of flow of fuel to said engine, a third branch conduit connecting said pair of branch conduits at points upstream of the restrictions therein, a check valve in said third branch conduit opening in the direction of flow from said one branch conduit to the other, spring means biasing said check valve closed in opposition to the difference between the fuel pressures acting on opposite sides thereof, said check valve being inoperable when said selector valve is in said second position and being operable to open position by said difference of fuel pressures when said selector valve is in said first position and said pressure differential exceeds a value determined by the characteristics of said spring means, whereby, when said pressure differential exceeds said value, the rate of flow of fuel to the engine is gradually increased to the same constant maximum value whether the selector valve is in its first or second position.

5. Fluid flow control apparatus, comprising a main conduit, a pair of parallel branch conduits connecting two spaced portions of said main conduit, a selector valve at one of the junctions of said branch conduits with said main conduit, said selector valve being movable between a first position wherein only one of said branch conduits is open and a second position wherein both of said branch conduits are open, metering restrictions in each of said branch conduits for determining the rate of fuel flow to the engine throughout its operating range, said selector valve being effective upon movement to said first and second positions to establish respectively first and second relationships between the fluid pressure differential between said portions of said main conduit and the rate of flow of fluid therethru, a third branch conduit connecting said pair of branch conduits at points between said selector valve and said restrictions, a check valve in said third branch conduit opening in the direction of flow from said one branch conduit to the other, spring means biasing said check valve closed in opposition to the difference between the fluid pressures acting on opposite sides thereof, said check valve being inoperable when said selector valve is in said second position and being operable to open position by said difference of fluid pressures when said selector valve is in said first position and said pressure differential exceeds a value determined by the characteristics of said spring means, whereby, when said pressure differential exceeds said value, the rate of flow of fluid thru said main

conduit is gradually increased to the same constant maximum value whether the selector valve is in its first or second position.

6. Fluid flow control apparatus, comprising a main conduit, a pair of parallel branch conduits connecting two spaced portions of said main conduit, a selector valve at the upstream junction of said branch conduits with said main conduit, said selector valve being movable between a first position wherein only one of said branch conduits is open and a second position wherein both of said branch conduits are open, metering restrictions in each of said branch conduits for determining the rate of fuel flow to the engine throughout its operating range, said selector valve being effective upon movement to said first and second positions to establish respectively first and second relationships between the fluid pressure differential between said portions of said main conduit and the rate of flow of fluid therethru, a third branch conduit connecting said pair of branch conduits at points between said selector valve and said restrictions, a check valve in said third branch conduit opening in the direction of flow from said one branch conduit to the other, spring means biasing said check valve closed in opposition to the difference between the fluid pressures acting on opposite sides thereof, said check valve being inoperable when said selector valve is in said second position and being operable to open position by said difference of fluid pressures when said selector valve is in said first position and said pressure differential exceeds a value determined by the characteristics of said spring means, whereby, when said pressure differential exceeds said value, the rate of flow of fluid thru said main conduit is gradually increased to the same constant maximum value whether the selector valve is in its first or second position.

7. A fuel supply system for an internal combustion engine, comprising a main conduit for fuel flowing to said engine, a pair of parallel branch conduits connecting two spaced portions of said main conduit, a selector valve at one of the junctions of said branch conduits with said main conduit, said selector valve being movable between a first position wherein only one of said branch conduits is open and a second position wherein both said branch conduits are open, metering restrictions in each of said branch conduits, means for controlling the fuel pressure differential between said portions of said main conduit, said selector valve being effective upon movement to said first and second positions to establish respectively first and second relationships between said fuel pressure differential and the rate of flow of fuel to said engine, a passage connected in parallel with said metering restrictions, an enrichment valve in said passage movable in an opening direction by said fuel pressure differential, spring means biasing said enrichment valve closed, stop means for limiting the opening movement of said enrichment valve, a third branch conduit connecting said pair of branch conduits at points between said selector valve and said restrictions, a check valve in said third branch conduit, spring means biasing said check valve closed, said check valve being inoperable when said selector valve is in said second position and being operable to open position by the fuel pressure differential when said selector valve is in said first position and said pressure differential exceeds a value determined by the characteristics of said spring means, said check valve being also so adapted that, when said pres-

sure differential exceeds said value, the rate of flow of fuel to the engine is substantially the same whether the selector valve is in its first or second position.

8. A fuel supply system for an internal combustion engine, comprising a main conduit for fuel flowing to said engine, a pair of parallel branch conduits connecting two spaced portions of said main conduit, a selector valve at one of the junctions of said branch conduits with said main conduit, said selector valve being movable between a first position wherein only one of said branch conduits is open and a second position wherein both said branch conduits are open, metering restrictions in each of said branch conduits, means for controlling the fuel pressure differential between said portions of said main conduit, said selector valve being effective upon movement to said first and second positions to establish respectively first and second relationships between said fuel pressure differential and the rate of flow of fuel to said engine, a passage connected in parallel with said metering restrictions, an enrichment valve in said passage movable in an opening direction by said fuel pressure differential, spring means biasing said enrichment valve closed, stop means for limiting the opening movement of said enrichment valve, a third branch conduit connecting said pair of branch conduits at points between said selector valve and said restrictions, a check valve in said third branch conduit opening in the direction of flow from said one branch conduit to the other, spring means biasing said check valve closed in opposition to the difference between the fuel pressures acting on opposite sides thereof, said check valve being inoperative when said selector valve is in said second position and being operable to open position by said difference of fuel pressures when said selector valve is in said first position and said pressure differential exceeds a value determined by the characteristics of said spring means, said check valve being also so adapted that, when said pressure differential exceeds said value, the rate of flow of fuel to the engine is substantially the same whether the selector valve is in its first or second position.

9. Fluid flow control apparatus, comprising a main conduit, a pair of parallel branch conduits connecting two spaced portions of said main conduit, a selector valve at one of the junctions of said branch conduits with said main conduit, said selector valve being movable between a first position wherein only one of said branch conduits is open and a second position wherein both of said branch conduits are open, metering restrictions in each of said branch conduits, said selector valve being effective upon movement to said first and second positions to establish respectively first and second relationships between the fluid pressure differential between said portions of said main conduit and the rate of flow of fluid therethru, a passage connected in parallel with said metering restrictions, a valve in said passage movable in an opening direction by said fluid pressure differential, spring means biasing said last-mentioned valve closed, stop means for limiting the opening movement of said last-mentioned valve, a third branch conduit connecting said pair of branch conduits at points between said selector valve and said restrictions, a check valve in said third branch conduit opening in the direction of flow from said one branch conduit to the other, spring means biasing said check valve closed in opposition to the difference between the fluid

pressures acting on opposite sides thereof, said check valve being inoperative when said selector valve is in said second position and being operable to open position by said difference of fluid pressures when said selector valve is in said first position and said pressure differential exceeds a value determined by the characteristics of said spring means, said check valve also being so adapted that, when said pressure differential exceeds said value, the rate of flow of fluid thru said main conduit is substantially the same whether the selector valve is in its first or second position.

10. A fuel supply system for an internal combustion engine, comprising manual mixture control means for selectively supplying fuel to said engine at an automatically regulated lean mixture rate or rich mixture rate, means for automatically proportioning both mixture rates in response to the power output of said engine, means for progressively enriching both mixture rates commencing at the same value of said power output, first additional means for further enriching the lean mixture rate in the high power output range of the engine and second additional means for making both mixture rates attain the said maximum value which remains constant throughout a substantial portion of the high power output range of said engine.

11. A fuel supply system for an internal combustion engine, comprising manual mixture control means for selectively supplying fuel to said engine at an automatically regulated lean mixture rate or rich mixture rate, means for automatically proportioning both mixture rates to the power output of said engine, means responsive to said power output for progressively enriching both mixture rates commencing at the same value of said power output, first additional means responsive to high power output of said engine for automatically further increasing the lean mixture rate when said manual control means is set to supply fuel at a lean mixture rate, and second additional means for making both mixture rates attain the same maximum value which remains constant throughout a substantial portion of the high power output range of said engine.

12. A fuel supply system for an internal combustion engine, comprising manual mixture control means for selectively supplying fuel to said engine at an automatically regulated lean mixture rate or rich mixture rate, valve means for automatically enriching both mixture rates in proportion to the power output of said engine, means responsive to said power output for progressively enriching both mixture rates commencing at the same value of said power output, first additional valve means for further increasing the lean mixture rate, and second additional means for making the maximum lean mixture rate the same as the maximum rich mixture rate throughout a substantial portion of the high power output of said engine.

13. A fuel supply system for an internal combustion engine, comprising a manual mixture control, movable between lean and rich mixture positions, for selectively controlling the supply of fuel to said engine at an automatically regulated lean mixture rate or rich mixture rate, in accordance with the power output of the engine, and valve means adapted to commence opening at the same value of said power output and enrich both mixture rates at progressively increasing rates, and stop means to limit the opening of said valve means so as to obtain the same constant mixture

rate at high power outputs of said engine, regardless of the position of said manual mixture control.

14. A fuel supply system for an internal combustion engine comprising manual mixture control means for selectively supplying fuel to said engine at an automatically regulated lean mixture rate or rich mixture rate, means for coordinately enriching both mixture rates in response to the power output of the engine beginning at the same value of said power output, first additional means for further enriching the lean mixture rate at a higher rate than the enrichment rate of the rich mixture rate, and second additional means for maintaining both mixture rates at the same constant maximum value throughout a substantial portion of the high power output range of said engine.

15. A fuel supply system for an internal combustion engine comprising manual mixture control means for selectively supplying fuel to said engine at an automatically regulated lean mixture rate or rich mixture rate, means for coordinately enriching both mixture rates in response to the power output of the engine beginning at the same value of said power output, regardless of whether the manual control means is functioning to supply a lean or rich mixture rate, and stop means to limit the range of operation of said enriching means and maintain both mixture rates at the same constant maximum value throughout a substantial portion of the high power output range of said engine.

16. A fuel supply system for an internal combustion engine comprising manual mixture control means for selectively supplying fuel to said engine at an automatically regulated lean mixture rate or rich mixture rate, means for proportioning both mixture rates in response to the power output of the engine, valve means for enriching both mixture rates at the same increasing rate

throughout a substantial portion of the power output range of the engine, additional valve means to further increase the enrichment rate of the lean mixture rate throughout a substantial portion of the higher power output range of the engine, and means for maintaining both mixture rates at the same constant maximum value throughout a substantial portion of the high power output range of the engine.

17. A fuel supply system for an internal combustion engine comprising manual mixture control means for selectively supplying fuel to said engine at an automatically regulated lean mixture rate or rich mixture rate, valve means for coordinately enriching both mixture rates in response to the power output of the engine, additional valve mechanism, responsive to the power output of the engine, for further enriching the lean mixture rate, and adapted to open at the same value of said power output, regardless of whether the manual control means is functioning to supply a lean or rich mixture rate, and stop means to limit the maximum opening of said valve mechanism and thereby limit the maximum enrichment of the mixture rates to a selected value.
